[57] CLAIM

The ornamental design for a faucet set, as shown and described.

DESCRIPTION

FIG. 1 is a perspective view taken from the top, front and left side of a faucet set showing my new design;
FIG. 2 is a front elevational view of the spout thereof;
FIG. 3 is a left side elevational view of FIG. 2;
FIG. 4 is a right side elevational view of FIG. 2;
FIG. 5 is a rear elevational view of FIG. 2;
FIG. 6 is a top plan view of FIG. 2;
FIG. 7 is a side elevational view of one handle thereof, the other sides being the same as the side shown; and
FIG. 8 is a top plan view of FIG. 7.
The fragmentary broken line showing of a lavatory in FIG. 1 is for purposes of illustration only and forms no part of the claimed design.
